J. W. JOHNSTON.
REFILLABLE CARTRIDGE FUSE,
FILED DEC. 22, 1919.

James W. Johnston
INVENTOR

BY *J. M. Thomas*
ATTORNEY

UNITED STATES PATENT OFFICE.

JAMES W. JOHNSTON, OF SALT LAKE CITY, UTAH.

REFILLABLE CARTRIDGE FUSE.

Application filed December 22, 1919. Serial No. 346,693.

To all whom it may concern:

Be it known that I, JAMES W. JOHNSTON, a citizen of the United States, residing at Salt Lake City, in the county of Salt Lake and State of Utah, have invented certain new and useful Improvements in Refillable Cartridge Fuses, of which the following is a specification.

My invention relates to electric fuses, and has for its object to provide an inclosed or cartridge fuse of the refillable type, which is economical and simple in construction, easily and quickly assembled to replace a burned out fuse and whereby the electric contact is efficiently secured by the gripping of the end portions of the fuse element when assembling the device.

These objects I accomplish with the device illustrated in the accompanying drawings in which similar letters and numerals of reference indicate like parts throughout the several figures and as described in the specification forming a part of this application and pointed out in the appended claims.

In the drawings in which I have shown a substantial embodiment of my invention, Figure 1 is a longitudinal section of the device. Figure 2 an end elevation of my device with the jam collar and one of the contact members removed. Figure 3 is an end elevation of my device with the jam cap in place thereon. Figures 4 and 5 are an edge elevation and plan view respectively of one form of the contact and gripping members.

My invention consists in the assembling and construction of the elements required to provide a cartridge for an inclosed fuse member which member may be quickly replaced when melted, and consists of a cylinder 1 made of insulating material and externally threaded at each end. Two diametrically opposed recesses 2 are cut in each end of said cylinder. An internally threaded sleeve 3 is screwed on each end of said cylinder and each has an externally threaded portion 4 thereon with the end thereof partially closed by an inwardly turned flange 5. A recess 6 is cut in said flange 5 with a purpose to be hereafter explained, and in screwing said sleeves on said cylinder 1 the said recess 6 is to be positioned at right angles to said recesses 2 in the ends of said cylinder. Internally threaded jam collars 7 are screwed on the externally threaded portion 4 of said sleeves 3, and each has

its end cut out to form a bearing face or seat 8. I provide coating gripping jam collars or caps 7. Each of the contact members A has a portion thereof shown at 9 shaped and bent to engage in said recesses 2 of the cylinder and the side edge of each also engages in the said recess 6 of the sleeves 2. In the said contact member A the said portions 9 are made longer and extend 65 as gripping fingers 11. The said fingers 11 are to be slipped between the jaws of any knife connection as terminals. On the inner curved side of each of said members A is provided the segment member 13, each of 70 which is given the form of a segment of a sphere and is to bear against the said face or seat 8 of the jam collars 7. The fuse member or link 14 which is used within the cartridge has its end portions firmly held 75 between the pair of coating contact members A and may take any of the commonly used forms, and consists of a strip of easily melted fuse material having one or more weakened portions adapted to melt when 80 subjected to more than a predetermined amperage. In the end of each cone shaped segment 13 I provide ventilating holes 10 opening to the interior of the cartridge.

The assembling of my device is as follows: The sleeves 3 are screwed on the end portions of the insulating cylinder 1 with the portions 4 extended to receive the jam collars 7. The pair of contact members A are then placed loosely in position, within 90 the end of said portion 4, by engaging the curved portion 9 in the respective recesses 2 and 6, and partially screwing one of said jam collars 7 on that end of my device, this will hold said contact members A in place 95 I then insert the fuse member 14 with one end portion between the pair of contact members 9 as shown in Figure 3 and then insert another one of said contact members A into the portion 4 of the other end of my 100 device, as shown in Figure 2, and when the other of said contact members A is inserted at that end I screw on the other jam collar 7 and tighten both of them. The tightening of said jam collars with their cone shaped 105 faces 8 bearing against the segment members 13 will cause the contact members A to grip the end portions of the fuse member 14 firmly and without any tendency to twist the said fuse member 14. To refill 110 the cartridge when the fuse member 14 is burned out I simply loosen each of said

jam collars 7 and the parts of the burned out fuse member 14 will fall out, and a new member 14 may be easily and quickly placed in position and the said jam collars tightened or screwed up.

I thus provide a new and efficient cartridge fuse within which the fuse member may be quickly placed and rigidly held by new and novel gripping members to make 10 an electric safety fuse without bending, bolting or twisting the fuse member.

Having thus described my invention I desire to secure by Letters Patent and claim:

1. A refillable cartridge fuse comprising 15 a casing having recesses in its edges and external threads on each end portion; a fuse link carried in said casing; a partial closure screwed on said threads of said casing and having a radially disposed slot in the end 20 portion of each; contact members with a portion of each engaged in said recesses and slots; and jam collars to cause said contact members to grip the end portions of said fuse when screwed on said closure members.

2. A refillable fuse comprising a casing 25 having recesses in its end portions; a flanged sleeve on each end of said casing having a recess in the flanged portion; a jam collar on each of said sleeves; coating contact members adapted to engage in said recesses 30 and to form terminals; and a fuse link having its end portions gripped by said contact members when said collars are tightened on said sleeves.

3. A refillable fuse cartridge comprising 35 a casing having recesses in its edges; a fuse link carried therein; a partial closure for each end of said casing and having a radially disposed slot in the end portions thereof; contact members with portions engaged 40 in said recesses and slots and adapted to be forced toward each other to grip said fuse link; and means to force said contact members toward each other.

In testimony whereof I have affixed my 45 signature.

JAMES W. JOHNSTON.
